UNITED STATES PATENT OFFICE.

ELLERY JOHNSON, OF BROOKLYN, NEW YORK.

TYPE-WRITER REST.

1,264,654.

Specification of Letters Patent. Patented Apr. 30, 1918.

Application filed July 7, 1916. Serial No. 107,986.

To all whom it may concern:

Be it known that I, ELLERY JOHNSON, a citizen of the United States, residing at Brooklyn, in the county of Kings and State 5 of New York, have invented a new and useful Improvement in Type-Writer Rests, of which the following is a specification.

The principal objects of this invention are to provide rests for typewriters which shall be more efficient and convenient in use than those heretofore constructed and which shall have a general organization wherein a resilient or elastic action is interposed between the typewriter and its supporting table, desk 10 or such and thus prevent the vibrations of the machine from reaching the supporting board of the desk which would, in the absence of my invention, tend to greatly magnify the sound resulting from the vibrations. 15 Furthermore I provide a hinging action in the device by which the typewriter can be easily and quickly tilted out of the way to allow the surface of the desk to be readily cleaned of dust, particles of paper, etc., 20 which usually collect there.

Referring to the accompanying drawings Figure 1 is a side view of my device attached to a section of table or desk and supporting one side of a typewriter, there being one of 30 the devices at each side; Fig. 2 a section taken at $x-x$; Fig. 1; Fig. 3 a plan view of the device proper and Fig. 4 a perspective view of a leaf or flat spring having a corrugated spring superimposed thereon.

1 is a fulcrum-plate having at its rear end a pair of ears 2 and at its front end ears 2¹. Placed underneath, at each end, is a rubber cushion 3 and at the center is a clamp 4 secured to the desk by screws 5 which straddles the plate and holds it down upon the rubber cushions. The clamp has a pin 6 riveted thereto which passes downwardly through a hole in the fulcrum-plate to retain it in position. 7 is a supporting bar 40 having a channel-section formation and positioned above the fulcrum-plate and attached thereto by means of rivet 8 at its rear end and removable pin 8¹ at its front end. Centrally located upon this bar is a flat or leaf spring 9 fastened at its ends by rivets 10 and having slidably mounted thereon collars 11, the rivets being of sufficient length to allow of frictional contact of the col-

lars between the supporting bar 7 and leaf spring 9. Centrally located and secured 55 upon the leaf spring is a corrugated spring 12 upon which the typewriter rests which is held down upon it by the screws 13, these screws entering threaded holes which are commonly found in typewriters. These 60 screws pass through holes in the supporting bar 7 and have helical springs 14 interposed between the bar and washers resting upon the screw heads.

It will now be noted that the typewriter 65 is entirely supported by spring elements, certain of which are adjustable as the collars 11 may be moved to any position, as at 15, thus changing the amount of resilience to suit different weights of machines; for the 70 nearer the collars are placed to each other the stiffer the action of the leaf spring.

When wishing to clean under the typewriter pin 8¹ is removed and the typewriter with bar 7 raised, hinging upon fulcrum-pin 75 or rivet 8, as shown by dotted line 16.

I claim:

1. In a typewriter rest the combination of a stationary member; a second member having its rear end pivotally connected with the 80 said first member; resilient members carried by said second member and adapted to engage a typewriter frame and means for retaining engagement of said resilient members with a typewriter, substantially as described.

2. In a typewriter rest the combination of a rigid support; a resilient member mounted thereon consisting of a flat spring for supporting a typewriter and adjustable members supporting said spring, substantially 90 as described.

3. In a typewriter rest the combination of a rigid support; a resilient member centrally located thereon and adapted to engage a 95 typewriter; means for altering the amount of resilience of said centrally located resilient member, and resilient members mounted upon the rigid support and adapted to engage the typewriter frame and oppose the 100 action of the centrally located resilient member, substantially as described.

4. In a typewriter rest the combination of a supporting member; an adjustable resilient member mounted thereon; a second resilient 105 member carried by said adjustable resilient

member and adapted to engage a typewriter frame to support same and means for holding the typewriter in contact with said second resilient member, substantially as described.

5. In a typewriter rest the combination of a supporting frame; a centrally located

member having adjustable supports for engaging and receiving the weight of a typewriter and resilient members connecting 10 each end of the said supporting frame with the typewriter, substantially as described.

In witness whereof I affix my signature.
ELLERY JOHNSON.
